CLAIM

We claim the ornamental design for a control panel for a compressor, as shown and described.

DESCRIPTION

FIG. 1 is a perspective view of a control panel for a compressor that embodies the ornamental design of the present invention, the compressor being shown in broken line;

FIG. 2 is a perspective view of the control panel for a compressor of FIG. 1;

FIG. 3 is a front view of the control panel for a compressor of FIG. 1; and,

FIG. 4 is a top view of the control panel for a compressor of FIG. 1.

The broken line showings in FIGS. 1-4 are for illustrative purposes only and form no part of the claimed design.
